UNITED STATES PATENT OFFICE.

KENNETH DAVIS, OF ST. BENEDICT, PENNSYLVANIA, ASSIGNOR, BY MESNE ASSIGNMENTS, TO REMBRANDT PEALE, W. SANDERS DAVIES, AND WILLIAM S. WALLACE, TRUSTEES.

MECHANISM FOR DISINTEGRATING DISLODGED MATERIAL.

Application filed September 20, 1921. Serial No. 502,036.

The invention relates to means for disin-
5 tegrating or breaking up material which
after it has been preliminarily dislodged or
dejected is still in too compact a mass for
easy handling by a power shovel, for in-
stance.

10 Objects and advantages of the invention
will be set forth in part hereinafter and in
part will be obvious herefrom, or may be
learned by practice with the invention, the
same being realized and attained by means
of the instrumentalities and combinations
pointed out in the appended claims.

15 The invention consists in the novel parts,
constructions, arrangements, combinations
and improvements herein shown and de-
scribed.

20 The accompanying drawings, referred to
herein and constituting a part hereof, illus-
trate one embodiment of the invention, and
together with the description, serve to explain
the principles of the invention.

Of the drawings:—

25 Fig. 1 is a top plan of a device constructed
in accordance with the invention;

Fig. 2 is a side elevation looking at Fig. 1
from the direction of the bottom of the
sheet;

30 Fig. 3 is a greatly enlarged fragmentary
longitudinal vertical section taken on line
3—3 of Fig. 4;

Fig. 4 is a greatly enlarged transverse vertical
section, taken on line 4—4 of Fig. 1;

35 Fig. 5 corresponds to Fig. 3 but shows the
projector pushed upwardly into the dis-
lodged material at the beginning of the draw-
ing out movement of the device;

Fig. 6 is a diagrammatic elevation showing
40 the device in the undercut kerf in a coal
seam preparatory to the dislodgment of the
coal;

Fig. 7 is a diagrammatic top plan corre-
sponding to Fig. 6;

45 Fig. 8 is a diagrammatic elevation like Fig.
6 but showing the coal just dislodged; and

Fig. 9 is a like diagrammatic view showing
the projectors forced into the mass of dis-
lodged coal and the mass further disinte-
grated.

50 In the dislodgment of mineral from a vein
or deposit, it frequently occurs that as so
dislodged the material is not in a favorable

condition for most efficient handling. It is
also desirable that the preliminary dislodg-
ment be very gentle so as to avoid breakage, 55
and further disintegration is required for
later efficient handling. The present invention
is intended to permit the material to be
dislodged under the most favorable condi-
tions and to then gradually disintegrate the 60
dislodged material so that it can be handled
under the most favorable and efficient con-
ditions.

An example of the foregoing is found in the
mining of certain kinds of coal, especially 65
coal of a soft or friable nature. Such coal is
shot down, or otherwise dislodged, as gently
as possible to prevent any unnecessary or
avoidable breakage, and thus is usually in too
compact a mass to be expeditiously and effi-
ciently conveyed away. The present invention
70 is advantageously employed in connec-
tion with the mining of such coal and then
acts on the coal to prepare it for expeditious
and efficient removal, as by a loading machine
75 or power shovel.

When so acted upon, the coal is in favor-
able condition for being conveyed away for
instance by the loading machine of my co-
pending application Ser. No. 247,240, filed 80
July 29, 1918. Accordingly, the invention is
shown applied to the mining of coal, although
it will be understood that the description of
this particular application is exemplary and
explicative and is not restrictive of the in-
vention.

Referring now to the present preferred
embodiment of the invention, illustrated by
way of example in the accompanying draw-
ings, a low and flat frame is provided, adapt-
ed to lie beneath a mass of undermined ma-
terial, as for example, in an undercut kerf
beneath a mass of coal preparatory to its dis-
lodgment.

One or more projectors are carried either
directly or indirectly on said frame and
means are provided for forcing or project-
ing these projectors upwardly into the mass
of dislodged material, whereby it is exten-
sively yet gently further disintegrated as the
device is drawn outwardly and thus prepared
by power, and practically instantaneously,
100 for loading. A plurality of the devices are
preferably employed together, and are drawn

out simultaneously, and act together on the dislodged mass of material in the manner described. Other features of the invention will be first described in connection with the following detailed description.

Referring now in detail to the embodiment illustrated in the accompanying drawings, the frame of the device consists of a channel 1, which is low, flat and long, and has its back 2 adapted to lie on the ground, or on a mine or quarry floor, and the two side flanges 3 and 4 of the channel extend upwardly at either side and are utilized to mount or support other parts of the device.

15 A member or plurality of members, which may be conveniently styled projectors, are mounted on the frame in a convenient manner and are adapted to be projected upwardly into the mass of dislodged and dejected material, so that by drawing the device outwardly the mass of material will be further disintegrated.

20 As embodied, the projector or projectors are in cooperative relation with the means for drawing the device outwardly. A bar 5 lies within the channel 1, resting upon the bottom 2 thereof and it is preferably considerably narrower than the channel. Movable mounted on the frame are shown two projectors 6. A single description will be sufficient.

25 The projector is preferably pivotally mounted and as embodied consists of a generally U shaped or three-sided member narrower than, and lying within the channel bar 1, and having apertures near the two open ends, and also near one side thereof, as best appears from Figs. 2, 3 and 5. The projector is pivotally mounted on the frame by 30 means of rod 7 extending between and mounted in the sides 3 and 4 of the channel bar 1.

35 The projector or projectors comprise the two side reaches 8 and 9 and the front or cross reach 10. The cross reach 10 is preferably shallower or narrower than the side reaches, and across the top thereof there is formed an upwardly and outwardly extending flange 11, designed to assist in engaging the dislodged mass to lift or swing the projector 40 upwardly as the bar 5 is moved during the pulling outwardly of the device.

45 The embodied form of actuator for the projector comprises a cam 15, fastened upon the upper face of the bar 5 in any suitable manner, as by means of screws 16. A stop, such as a rod or bar 18 mounted in the sides 2 and 3 of the channel, is provided against which the front of the cam 15 impinges to stop the forward travel of the bar 5 relatively 50 to the channel, and to thereby cause the pull on the bar to move the entire device. In addition to the upward impulsion of the flange 11, the cam 15 pushes the projector bodily up into the mass of dislodged material.

55 60 65 The end of the bar 5 conveniently projects

beyond the front end of the channel and has means for attachment of a drawing cable, such as the hole 19 formed in the bar.

As embodied, a motor 20 is utilized to draw out the device from beneath the dislodged and dejected mass of material, the motor being provided with a winding drum 21, upon which is wound a cable 22, which has a hook 23, hooking into the hole 19. The motor is anchored in a suitable manner, as by being 70 braced against a jack-post 24, fastened preferably between the floor and roof when the device is being used in mine work.

In Fig. 6 (which, with Figs. 7, 8 and 9 are somewhat diagrammatic) a working face in 80 a mine is shown with an undercut kerf 27 into which the disintegrating device has been preparatorily inserted. By referring to Fig. 7, it will be seen that a battery or plurality of 85 the disintegrating devices may be utilized together, and simultaneously drawn outwardly to disintegrate an entire large dejected mass at one time. In Fig. 7 all the disintegrators are shown connected to a single winding mechanism, although this may be varied in 90 any convenient or desired manner. A hole 28 is shown in Fig. 6 for blasting powder or other disintegrating and dejecting means.

In Fig. 8 the mass is shown dejected and 95 preliminarily disintegrated, the disintegrating devices being in the position of Fig. 6, with the projectors 6 lying down within the channels 1.

In Figs. 7 and 9 the pull has been exerted on the disintegrators. Thereby the bar 5 has 100 moved outwardly, or to the left in Figs. 6 and 8, and the projectors 5 have been pushed upwardly into the disintegrated mass from the position of Figs. 6 and 8 to that of Fig. 9 by 105 the action of cam 15 on the projector 5 (the two positions being shown in detail in Figs. 3 and 5, respectively).

The continued pull after the projectors have been forced upwardly will further effect the disintegration of the whole mass, as 110 approximately and somewhat diagrammatically shown in Fig. 9. In coal mining this action will leave the coal in condition to be operated on efficiently by my loading machine hereinbefore referred to, while permitting 115 such a gentle dejection and preliminary disintegration as will yield a relative maximum of large pieces of coal.

The invention in its broader aspects is not limited to the specific mechanisms shown and 120 described but departures may be made therefrom within the scope of the accompanying claims without departing from the principles of the invention and without sacrificing its chief advantages.

125 What I claim is:—

1. A device for breaking up dislodged material comprising in combination two relatively slidable elements, a projector pivoted to one of the elements to swing up 130

wardly, a cam member, carried by the other element, engageable with the free end of the projector, the projector being pivoted so that when a pull is exerted on the said other element carrying the cam member, the projector swings about its pivot in a direction away from the direction of the pull.

2. A device for breaking up dislodged material comprising in combination two relatively slidable elements, a projector pivoted to one of the elements to swing upwardly, a cam member carried by the other element and engageable with the free end of the projector, the projector facing in such a direction that

15 when a pull is applied to said other member, the combined action of the cam and the resistance offered by the material, causes the projector to move toward the vertical position.

20 3. A device for breaking up dislodged material comprising in combination two relatively slidable elements, a projector pivoted to one of the elements to swing upwardly, and means, carried by the other of the elements, engageable continually with the projector at the end opposite its pivot, for raising the projector upon relative movement of the two elements.

25 4. A device for breaking up dislodged material comprising in combination two relatively slidable elements, a projector pivoted to one of the elements to swing upwardly, a cam carried by the other of the elements, the cam having an upwardly inclined face, engageable continually with the projector at the end opposite its pivot, for raising the projector upon relative movement of the two elements.

30 5. A device for breaking up dislodged material comprising in combination two relatively slidable elements, a projector pivoted to the first of the elements to swing upwardly, means, carried by the second of said elements, engageable with the end of the projector opposite its pivot for pushing it upwardly upon relative movement of the two elements, and interengaging means carried by the two elements adapted to come into engagement after the projector is raised, whereby a continued pull on the second element first raises the projector and then acts to move the whole assembly.

35 6. A device for breaking up dislodged material comprising in combination a frame, a bar slidable with respect to the frame, a projector pivoted to the frame, means carried by the bar for engaging that end of the projector opposite its pivot, means carried by the bar for thereafter engaging the frame, whereby a continued pull on the bar first raises the projector and then acts to move the whole apparatus in the direction of the pull.

40 7. A device for breaking up dislodged material comprising in combination two relatively slidable elements, a U-shaped projector

pivoted at its open end to the first of the elements to swing upwardly, means, carried by the second of said elements, engageable with the other end of the projector for pushing it upwardly upon relative movement of the two elements, and interengaging means carried by the two elements adapted to come into engagement after the projector is raised, whereby a continued pull on the second element first raises the projector and then acts to move the whole assembly.

45 8. A device for breaking up dislodged material comprising a frame, a bar slidable with respect to the frame, a U-shaped projector pivoted at its open end to the frame to swing upwardly, means carried by the bar for engaging the closed end of the projector, and means carried by the bar for thereafter engaging the frame, whereby a continued pull on the bar raises the closed end of the projector, and then acts to move the whole device in the direction of the pull.

50 9. A device for breaking up dislodged material comprising a frame, a bar slidable with respect to the frame, a U-shaped projector, made of a bent plate, pivoted at its open end to the frame with the sides of the plate disposed vertically, and means, carried by the bar engageable with the U-shaped projector at its closed end, for raising it, upon relative movement of the frame and bar.

55 10. A device for breaking up dislodged material comprising a frame, a bar slidable with respect thereto, a U-shaped projector, made of a bent plate, pivoted at its open end to the frame, with the sides of the plate disposed vertically, and means carried by the bar and engageable first with the projector and then with the frame, whereby a continued pull on the bar first raises the projector and then moves the frame.

60 11. A device for breaking up dislodged material and adapted to underlie the dislodged material, and including in combination two relatively movable members, a movable projector mounted on one of said members, a projection mounted on the other of said members, and means whereby said members may be relatively moved to force the projector upwardly directly into the mass of material by engagement with said projection, the projection continuously supporting the projector while it is being forced into the material.

65 12. A device for breaking up dislodged material and adapted to underlie the dislodged material, and including in combination two relatively movable members, a movable projector mounted on one of said members, a projection mounted on the other of said members, and means whereby said members may be relatively moved to force the projector upwardly directly into the mass of material by engagement with said projection, the projection continuously supporting the

projector while it is being forced into the material, and holding the projector in said upward engaged position while the entire device is drawn outwardly to disintegrate the material.

13. A device for breaking up dislodged material and adapted to underlie the dislodged material, and including in combination two relatively movable members, a movable projector mounted on one of said members, a projection mounted on the other of said members, and means whereby said members may be relatively moved to force the projector upwardly directly into the mass of material by engagement with said projection, the projection continuously supporting the projector while it is being forced into the material, and means for stopping the relative movement after the projector has been forced upwardly into the material and for causing the device to move as an entirety to disintegrate the material.

14. A device for breaking up dislodged material and adapted to underlie the dislodged material and including in combination a low flat frame, having two relatively movable members, a movable disintegrating projector mounted on one of said members, an inclined projection on the other member adapted to support and to force the projector upwardly into the dislodged material, and means for arresting said relative movement to cause the device to move as a whole to effect the disintegration of the dislodged material.

15. A device for breaking up dislodged material and adapted to underlie the dislodged material and including in combination a low flat frame, having two relatively movable members, a movable disintegrating projector mounted on one of said members,

to move upwardly and inwardly, an inwardly and upwardly inclined projection on the other member adapted to support and to force the projector upwardly into the dislodged material, and means for arresting said relative movement to cause the device to move as a whole to effect the disintegration of the dislodged material.

16. A device for breaking up dislodged material and adapted to underlie the dislodged material and including in combination a low, flat frame having two relatively movable members, a projector mounted at its inner end on one of said members so that its outer end will swing upwardly, an inwardly and upwardly inclined projection on the other of said members, and operating during the relative movement of the members to support and to force the projector upwardly, and means for arresting said relative movement of the two members with the projector supported in the elevated position, and the entire device moved bodily.

17. A device for breaking up dislodged material and adapted to underlie the dislodged material and including in combination a low, flat frame having two relatively movable members, a projector mounted at its inner end on one of said members so that its outer end will swing upwardly, a projection on the other of said members, operating during the relative movement of the members to support and to force the projector upwardly, and means for arresting said relative movement of the two members with the projector supported in the elevated position, and the entire device moved bodily.

In testimony whereof, I have signed my name to this specification.

KENNETH DAVIS.
